FRANK R. SCOTT, OF PORTSMOUTH, OHIO, ASSIGNEE TO THE SELBY SHOE COMPANY, OF PORTSMOUTH, OHIO, A CORPORATION OF OHIO.

SHOE.

1,185,007.

Specification of Letters Patent.

Patented May 30, 1916.

Application filed October 12, 1915. Serial No. 55,541.

To all whom it may concern:

Be it known that I, FRANK R. SCOTT, a citizen of the United States, and resident of Portsmouth, in the county of Scioto and State of Ohio, have invented certain new and useful Improvements in Shoes, of which the following is a specification.

This invention relates to the structure of boots and shoes, and particularly to the structure of the insoles used therein.

The primary purpose of the invention is to embody an arch-supporting structure in boots and shoes, which will be soft and pliable. In some shoes which are constructed to have an arch-supporting effect, such effect is caused by providing an arch-supporting structure other than the shoe itself, while in others the arch-supporting structure is incorporated into the shoe structure, so that it is an inseparable part of the shoe. According to the present invention the arch-supporting structure is of the latter class, and comprises a piece of soft pliable leather or other equivalent sheet material arranged to underlie the shank portion of the insole and attached to the shoe upper at both sides of the shank portion so as to serve as a sling to support the shank portion of the insole. The upper and the arch-supporting piece, being directly connected with each other and being taut when in use, form a support for the arch of the foot, especially the inner side of the arch, that is, the left-hand side of the right foot and the right-hand side of the left foot; and this support is pliable in consequence of omitting connection between it and the inner marginal portion of the insole. In order to amplify the flexibility at this point, the inner marginal portion of the insole is skived to a thin edge. The anchorage for the arch-supporting piece is at the outer marginal portion of the shoe. The arch-supporting effect is amplified by springing the insole edgewise so as to cause the inner edge of the shank portion to bulge upwardly and press against the inner side of the arch of the foot.

Of the accompanying drawings, which illustrate the invention: Figure 1 represents a bottom plan view of an insole which is provided with the arch-supporting piece hereinbefore mentioned. Fig. 2 represents a bottom plan view of an outsole. Fig. 3 represents a cross section of the insole **in the** plane of line 2--3 of Fig. 1. Fig. 4 repre-

sents a cross section of the insole in the plane of line 4--4 of Fig. 1. Fig. 5 represents a cross section through a shoe and last after the inseam has been sewn, the plane of this section corresponding to line 3--3 of Fig. 1. Fig. 6 represents a cross section through the shoe and last in a plane corresponding to line 4--4 of Fig. 1.

The same reference characters indicate the same parts wherever they occur.

I will first describe the insole, which, because of certain new features of construction, constitutes the foundation of the invention. The insole is indicated at 10. In the present instance it is intended for a welt shoe and is therefore prepared in such manner as to provide a marginal feather 11, a lip 12, a channel 13, and a channel flap 14. In the conventional insole for welt shoes the lip and channel begin at one side of the heel-seat portion and extend continuously along one marginal portion of the insole, around the toe, and back along the other marginal portion of the insole to a point of the heel-seat portion substantially opposite the starting point. In the present instance, however, the lip and channel end, at the inner marginal portion of the insole, at a point which is substantially at the junction of the shank portion and forepart, this point being usually called the ball portion. On Fig. 1 this point is indicated at 15. The lip and channel extend around the forepart and along the outer marginal portion 16 of the shank portion, but the channel flap is snipped at 17. The inner marginal portion of the shank portion is skived to a thin edge 18, the area of the skived portion being defined by line 19 in conjunction with the edge 18.

A piece 20 of tough pliable material, such as upper leather, is arranged against the bottom of the shank portion of the insole. Although I have mentioned leather, other material such as duck or canvas could be used to provide the piece 20. The inner marginal portion of the piece 20 is creased or doubled, as indicated at 21, to provide a stitch-receiving lip or flange 22. In order to hold the lip or flange 22 in the desired position for receiving the inseam stitches the piece 20 is stitched close to the crease, the stitches 23 bridging across the crease so as to hold the material at opposite sides of the crease in doubled relation. The 110

stitches 23 do not need to be any stronger than is necessary to hold the creased member in the condition shown by Figs. 1 and 3, until the inseam of the shoe is sewn; and, so long as they hold the lip 22 in stitch-receiving position until the inseam is sewn, it does not matter whether they are ruptured by the relatively heavy stresses incidental to the inseam-sewing operation. The crease 10 21 is curved inwardly to conform or lie parallel to the incurved edge 18 of the insole, and the piece 20 is attached temporarily to the insole in such position that the lip 22 will be in line with the stitch-receiving lip 12 15 of the insole and form a continuation of the latter lip. As shown by Fig. 1, the lips 12 and 22 are arranged in abutting end-to-end relation at the point indicated at 15. In consequence of this arrangement 20 of the two lips, the sewing needle of an inseam sewing machine may pass from the lip 12 to the lip 22, or vice versa, and sew a continuous inseam from the heel seat to the heel seat, the lip 22 being thus caught by 25 the inseam stitches, just as though it were in fact integral with the lip 12.

In arranging the piece 20 against the insole, the outer marginal portion of the said piece is tucked into the channel 13 as shown 30 by Fig. 3, the piece 20 being creased as indicated at 24, and the crease being tucked into the angle formed by the channel and channel flap. This operation provides a stitch-receiving lip or flange 25 which lies 35 against the inner surface of the channel flap, and when the inseam stitches are sewn along the outer marginal portion of the shank portion, they pass through the piece 20 at the crease 24 and become anchored in 40 the latter as shown by Fig. 5. Any suitable means may be employed for temporarily attaching the piece 20 to the insole. For example, the piece 20 may be attached by cement as indicated at 26 in Fig. 3, or it 45 may be attached by short tacks indicated at 27 in Fig. 1, or by both cement and tacks. If tacks are used, they would preferably be pulled out as soon as the inseam had been sewn. The purpose in snipping the channel flap as indicated at 17 is to enable the channel flap, along the outer marginal portion of the shank portion, to stand away from the insole as shown by Fig. 3, while that portion of the channel flap which is 50 upon the forepart may lie close to the insole as shown by Fig. 4. This enables the lip or flange 25 of the piece 20 to remain in the position shown by Fig. 3 instead of being folded back as would be the case if 55 the contiguous portion of the channel flap were left in the position shown in Fig. 4, and the sewing of the inseam along the shank portion is therefore facilitated.

In using the insole which I have described, the laster would attach the same

temporarily to the bottom of a last 28, as, by driving tacks through the insole into the last. The insole would be placed upon the last in such relation that the heel portion would be offset laterally, toward the 70 outer side of the last from final position, and the forepart of the insole would be fastened to the last, leaving the heel of the insole unfastened for the time being. The laster would then spring the heel portion to 75 the position indicated by dotted lines in Fig. 1, thus creating a fullness in the shank portion of the insole along the inner side of the latter, and such fullness would be pressed against the last so as to conform to 80 the arch formation.

A shoe upper is indicated at 29 in Figs. 5 and 6. I have not attempted to differentiate between the leather and the lining of the upper, and the element 29 may be regarded as comprising both of these elements. When the lasting operation has been finished, the shoe is ready for the inseam sewing operation. In consequence of sewing the inseam and of attaching a welt strip 30 simultaneously therewith, the outer marginal portion of the piece 20 is caught by the inseam stitches 31 and is thereby anchored to the insole and to the other elements of the between substance along the outer marginal portion of the shank portion. The welt strip is continuous from the heel-seat portion at one side of the shoe, along that side and around the toe and along the opposite side to the heel-seat portion. Around the 95 forepart of the shoe the inseam stitches 32 pass through the welt, the pulled-over portion of the upper, and the between substance of the insole, as shown by Fig. 6. Along the inner side of the shank portion of the shoe 100 the inseam stitches 33 pass through the welt, the pulled-over portion of the upper, and the creased portion 21 of the piece 20, but not through any portion of the insole. (See Fig. 5). The upper and the piece 20 are 105 thus directly connected with each other in a taut condition, forming a sling, as it were, for supporting the inner marginal portion of the insole. If tacks 27 are employed to hold the piece 20 in the desired position 110 against the insole, they may be withdrawn after the inseam has been sewn. If cement is used to hold the piece 20, it will not prevent the inner marginal portion of the insole from "creeping" relatively to the piece 115 20 and upper when the shoe is in use; for although it may be sufficient to hold the piece 20 to the insole prior to use of the shoe, the connection afforded by it would become ruptured in consequence of use of 120 the shoe, and the inner marginal portion would therefore become automatically freed from the contiguous portion of the piece 20 in consequence of use. This freedom to 125 creep, and the fact that the inner marginal 130

portion of the insole is skived to a thin edge along the shank portion, make the arch-supporting structure pliable and capable of conforming to the shape of the arch portion of the foot.

- As hereinbefore explained, the inner marginal portion of the insole receives an arch formation in consequence of springing the heel portion of the insole as indicated by dotted lines in Fig. 1. Such arch formation may be reinforced by likewise springing the outsole 34. For example, the excess stock of the insole having been trimmed as is customary after the inseam has been sewn, and the shoe is otherwise prepared for the reception of the outsole, the forepart of the latter would be temporarily fastened to the shoe, leaving the shank and heel portions unfastened for the time being, but offset laterally toward the outer side of the shoe from the position which they will ultimately occupy. After the forepart of the outsole has been fastened as just stated, the heel portion would be sprung toward the inner side of the shoe as indicated by dotted lines in Fig. 2, thus causing an arch formation along the inner marginal portion of the shank portion, conforming to that of the insole. The arch formation would be fixed 30 in consequence of stitching the outsole and permitting the shoe to dry on the last.
- A shoe made in accordance with the method hereinbefore described will have two distinct arch-supporting formations. First, that caused by springing both soles or the insole alone, and, second, that caused by the conjoint effect of the piece 20 and upper 29. The pliability of the arch-supporting structure is due in part to the skiving of the inner marginal portion of the insole and in part to the omission of connecting means between said portion and the other elements of the shoe; but the shoe is not weakened in consequence of such omission, because the piece 20 forms a continuation of the upper and is anchored by the inseam stitches 31 along the outer marginal portion of the shank portion of the shoe.
- The scope of the invention, so far as the piece 20 is concerned, is not necessarily limited to passing the inseam stitches 31 through the outer marginal portion of the shank portion of the insole, for if it were desired to omit the stitch-receiving element 55 from the outer marginal portion of the shank portion of the insole, the outer marginal portion of the piece 20 would nevertheless be united by the stitches 31 with the upper and welt strip along the outer side 60 of the shoe, and would form a connection substantially like that which includes the inseam stitches 33 in Fig. 5. For most purposes, however, I consider it preferable to provide the outer marginal portion of 65 the shank portion of the insole with a stitch-

receiving element and to pass the inseam stitches 31 therethrough as shown by Fig. 5. The outward appearance of the shoe is not altered by the inclusion of the piece 20, and the continuity of the welt strip is not interrupted. The inseam sewing operation is performed just as though the lip 12 of the insole were continued along the inner marginal portion of the shank portion, and the usual inseam stitches are all that is required 70 to attach the piece 20.

I claim:

1. In combination, an insole having an inseam lip on its forepart, one end of said lip being at the inner marginal portion of the junction of the shank portion and ball portion, and a piece of relatively limber sheet material arranged against the bottom of said shank portion, said piece being substantially coextensive with said shank portion, 80 the inner marginal portion of said piece being arranged to form a continuation of said lip, the outer marginal portion being arranged to be caught by the inseam stitches 85 near the outer edge of said shank portion, 90 and means temporarily connecting said piece with said insole to keep them in the desired relation.

2. In combination, an insole having an inseam lip on its forepart, one end of said lip being at the inner marginal portion of the junction of the shank portion and ball portion, a piece of relatively limber sheet material arranged against the bottom of said shank portion, said piece being substantially 100 coextensive with said shank portion, the inner marginal portion of said piece being arranged to form a continuation of said lip, and means forming a rupturable connection 105 between said shank portion and said piece.

3. In combination, an insole having an inseam lip extending around the forepart and along the outer marginal portion of the shank portion, one end of said lip being at the inner marginal portion of the junction of the 110 shank portion and ball portion, and a piece of relatively limber sheet material arranged against the bottom of said shank portion, said piece being substantially coextensive with said shank portion, the inner marginal 115 portion of said piece being arranged to form a continuation of said lip, the outer marginal portion of said piece being arranged to be caught by the inseam stitches which pass through said lip along the outer marginal portion of said shank portion.

4. In combination, an insole having an inseam lip, an inseam channel, and a channel flap, extending around the forepart and along the outer marginal portion of the shank portion, one end of said lip and flap being at the inner marginal portion of the junction of the shank portion and ball portion, and a piece of relatively limber sheet material arranged against the bottom of said shank por- 120 125 130

- tion, said piece being substantially coextensive with said shank portion, the inner marginal portion of said piece being arranged to form a continuation of said lip, said piece 5 having a crease arranged in the angle of said channel and flap along the outer marginal portion of said shank portion, the outer marginal portion of said piece being arranged to be caught by the inseam stitches which pass 10 through said lip and flap along the outer marginal portion of said shank portion.
5. In combination, an insole having an inseam lip extending along the outer marginal portion of the shank portion and around the 15 forepart to the junction of the shank portion and ball portion at the inner marginal portion of the insole, said lip ending at said junction, and a piece of relatively limber sheet material arranged against the bottom 20 of said shank portion, said piece being substantially coextensive with said shank portion, said piece having an incurved crease extending substantially longitudinally of the insole and substantially in line with said lip, 25 the inner marginal portion of said piece, as defined by said crease, being arranged to form a continuation of said lip, and stitches bridging across said crease and connecting said inner marginal portion of said piece 30 with the body portion of said piece to hold said inner marginal portion in position to be caught by the inseam stitches, the outer marginal portion of said piece being arranged to be caught by the inseam stitches 35 which pass through said lip along the outer marginal portion of the shank portion.
6. A shoe comprising an upper, an insole, a welt strip, and a piece of relatively limber sheet material arranged against the bottom 40 of the shank portion of said insole, said welt strip extending along the inner and outer sides of the shank portion of the shoe, said piece, said insole, said upper, and said welt strip, being connected along the outer 45 side of the shank portion of the shoe, and the inner marginal portion of said piece, the inner marginal portion of said upper, and said welt strip being united by inseam stitches, said insole being free from said 50 stitches.
7. A shoe comprising an upper, an insole, a welt strip, and a piece of relatively limber sheet material arranged against the bottom 55 of the shank portion of said insole, said welt strip extending along the inner and outer sides of the shank portion of the shoe, said piece, said insole, said upper, and said welt
- strip, being connected along the outer side of the shank portion of the shoe, the inner marginal portion of said piece and the inner 60 marginal portion of said upper being arranged to extend away from the bottom of said insole to form a stitch-receiving flange, and being united with said welt strip by inseam stitches, said insole being free from 65 said stitches.
8. A shoe comprising an upper, an insole, a welt strip, and a piece of relatively limber sheet material arranged against the bottom of the shank portion of said insole, said welt 70 strip extending along the inner and outer sides of the shank portion of the shoe, the inner marginal portion of said piece being arranged to extend away from said insole to form a stitch-receiving flange, said welt 75 strip being arranged in co-operative relation to said marginal portion to form the inseam, and the inner marginal portion of said upper being arranged between said welt strip and said portion of said piece, said welt 80 strip and said two portions being united by inseam stitches, said insole being free from said inseam stitches, said upper, said insole, said welt strip, and said piece being connected along the outer side of the shank 85 portion of the shoe.
9. A shoe comprising an upper, an insole, a welt strip, and a piece of relatively limber sheet material arranged against the bottom of the shank portion of said insole, said welt 90 strip extending around the forepart and along the inner and outer sides of the shank portion of the shoe, said insole having an inseam lip extending along the outer marginal portion of the shank portion and 95 around the forepart, one end of said lip being at the inner marginal portion of the junction of the ball portion and shank portion of the insole; the inner marginal portion of said piece being arranged to form a 100 continuation of said lip; the latter said portion, said upper, and said welt strip being united by inseam stitches along the inner side of the shank portion of the shoe; said 105 insole being free from said stitches; said piece, said upper, and said welt strip being united by inseam stitches along the outer side of the shank portion of the shoe; said welt, said lip, and said upper being united 110 by inseam stitches around the forepart of the shoe.

In testimony whereof I have affixed my signature.

FRANK R. SCOTT.
